UNITED STATES PATENT OFFICE.

ROBERT BINNIE, OF BOLIVAR, PENNSYLVANIA.

ROTARY RECIPROCATING DRILL.

Application filed September 25, 1923. Serial No. 664,673.

To all whom it may concern:

Be it known that I, ROBERT BINNIE, a citizen of the United States, and a resident of Bolivar, in the county of Westmoreland and State of Pennsylvania, have invented a new and useful Improvement in Rotary Reciprocating Drills, of which the following is a specification.

This invention relates to drills and particularly to rotary-reciprocating drills of the type used for drilling rock and other similar material.

It is an object to provide a drill which is simple, strong, durable and efficient in operation, and adapted to be driven by a motor mounted directly thereon.

It is a special object to provide a drill having a composite reciprocating drill rod, which is equipped with a plurality of hammers for delivering successive sharp blows to the part carrying the drill bit.

It is also a special object to provide a drill of the character referred to which may be easily assembled and disassembled, in which the several parts forming the drill rod and the hammers associated therewith are in substantial alignment, and in which the several parts including the driving and regulating mechanism are compactly and conveniently arranged.

A still further special object is to provide an improved construction for maintaining the drill bit in operative relation with the drill rod regardless of its insertion or withdrawal from the material being operated upon, as well as to provide a unique form of impact hammer consisting of a plurality of parts which can be assembled and disassembled without the employment of special attaching or locking devices in the form of bolts, screws, or the like.

An additional special object is to provide a drill adapted to be actuated by a driving motor mounted directly upon and forming a part of a combined bearing and closure unit for the casing whereby removal of the said unit accomplishes both the disconnection of the motor and a partial disassembling of the driving mechanism proper.

These and other objects of the invention will more fully appear when taken in conjunction with the following description and the appended claims.

The preferred embodiment of the inven-

tion is illustrated in the accompanying drawings in which Fig. 1 is a vertical sectional view with parts in elevation; Fig. 2 a transverse sectional view with parts in elevation, taken on the line II—II of Fig. 1; Fig. 3 a similar view taken on the line III—III of Fig. 1; Fig. 4 a detail fragmentary view of one of the impact hammers, showing the method of assembling the several parts; Fig. 5 a detail view showing the split collar employed in connection with the impact hammer shown in Fig. 4, said view being taken substantially on the line V—V of Fig. 1; Fig. 6 a fragmentary detail view showing the form and method of connection between the actuating pitman or connecting rod used in conjunction with the impact hammers, said figure being taken substantially on the line VI—VI of Fig. 1; Fig. 7 a detail view of the drill bit used in conjunction with the drill rod; and Fig. 8 an elevational detail view taken on the plane indicated by the lines VIII—VIII of Fig. 1.

In the embodiment illustrated, the guide frame 1 is provided with suitable means 2 for attaching it to a supporting standard 3. Mounted for sliding movement in the guiding slot 4 of frame 1 is a lug 5 depending from the casing 6. The lug 5 is internally threaded, and cooperating therewith is a screw 7, journaled at one end in the frame 1, and adapted to be rotated by means of hand crank 8. Extending inwardly from the frame 1 is a pair of oppositely disposed guiding ribs 9, 9', which engage suitably formed grooves in a pair of depending lugs 10, 10', respectively, formed upon the bottom of the casing 6.

The front end of the casing 6 is open, being closed by a closure plate 11 attached to the casing in any suitable manner as by the stud bolts 12. This closure plate is equipped with an inwardly extending bearing sleeve 13. A similar bearing sleeve 14 is removably supported in spaced relation to the sleeve 13 within the interior of the casing, the same being preferably bolted at 15 to a depending lug 16, and at 17 to an upstanding standard 18, formed integrally with the casing.

Mounted for rotary-reciprocating movement in the bearing sleeves 13 and 14 is a drill rod 19 which is flanged at its inner extremity 20 and provided with a longitudinal bore 21 which extends for a con-

siderable distance from its inner end and is circular in cross section. Interposed between the drill rod 19 and the bearing sleeves 13 and 14 are the respective bushings 22 and 23, the former being provided with the radially extending attached terminal flange 24 while the latter is likewise equipped with a similar terminal flange 25 these terminal flanges facing each other and being spaced apart a slight distance in which is disposed the worm wheel 26, said worm wheel being in abutting relation with the terminal flanges of the bushings whereby to be held against longitudinal movement. The worm wheel 26 is splined to the drill rod as indicated at 27 so as to be operatively engaged with the rod while permitting free sliding movement thereupon.

20 Journalled for sliding movement at the rear end of the casing 6 in any suitable bearing 28 is one end of an impact rod 29, the opposite end of which slidingly fits within the bore 21 of the drill rod, as clearly indicated in Fig. 1, the drill rod, the bearing 28, and the impact rod 29 being arranged in longitudinal alignment. The rod 29 is provided with an abutment 30 at a point adjacent the rear of the casing, and with a peripheral groove 31 spaced from the said abutment. Fitting within the groove 31 is a split collar, preferably consisting of two parts 32, 32', each being provided with a reduced portion and a radially flanged portion forming a shoulder. The sections 32, 32' are adapted to be held in cooperative relation within the groove 31 by means of a closed annulus 33 encircling the reduced portions of the collar and abutting against the flanges. Operatively engaging with the impact rod at a point intermediate the abutment 30 and groove 31 is a pitman or connecting rod 34, the said pitman being operatively associated with the impact rod due to the passage of the rod through an eyelet or opening 35 at one end thereof. Also threaded upon the rod 29 and abutting the opposite sides of the eyelet 35 are washers 36, 36', between which and the abutment 30 and the annulus 33 are disposed the respective compression springs 37, 37'.

55 Mounted for free sliding movement upon the rod 29 at a point adjacent the inner extremity of the drill rod is a reciprocating cylindrical sleeve 38, this sleeve being provided with a terminal flange 39 at one end, and with a peripheral groove 40 adjacent its opposite end. Fitting within the groove 40 is a sectional collar consisting of the sections 41, 41', constructed similarly to the collar sections 32, 32' and held in cooperative relation with the groove by means of an annulus 42, corresponding to the annulus 33. Likewise, engaging with the intermediate portion of sleeve 38 is the eyelet or

apertured extremity 43 of a connecting rod or pitman 44. Abutting washers 45, 45' are disposed at the opposite sides of the eyelet 43, and compression springs 46, 46' are interposed between these washers and the flange 39 and annulus 42, respectively.

50 The casing 6 at one side is provided with an opening 47 of considerable size which is adapted to be closed by a combined closure and bearing plate 48, the bearing being indicated at 49. This plate may be attached to the casing in any desirable way, as by the stud bolts 50, and has integrally formed therewith a motor supporting bracket the base 51 of which lies in substantial alignment with the bottom of the casing, as clearly shown in Fig. 3. An electric motor 52 is attached to the base 51 and has its armature shaft 53 projecting within the bearing 49, the extremity of the armature 85 shaft being non-circular in cross section, for a purpose to be presently described. Disposed at the opposite side of the casing and in alignment with the bearing 49 is a bearing 53, which may also be formed in a special bearing plate 54 attached to the casing as at 55. A crank shaft 56 is mounted within the casing with its opposite extremities journaled in the bearings 49 and 53. This crank shaft is equipped with two cranks 57 and 58, and has a worm 59 disposed at a point intermediate the said cranks, the worm 59 being adapted to operatively engage the worm wheel 26. The extremity of the crank shaft located within the bearing 49 is provided with a recess 60 corresponding in cross section to that of the non-circular extremity 53 of the armature shaft of the motor, the said recess receiving the end of the armature shaft, as indicated in Fig. 2, when the parts are assembled in operative relation.

55 The end of the pitman or connecting rod 34, opposite the eyelet 35 is operatively connected to the crank 58, while the corresponding end of the pitman or connecting rod 44 is similarly connected to the crank 57.

60 The outer extremity of the drill rod 19 is provided with a longitudinal cylindrical bore 61 extending inwardly from the bifurcated extremity forming the oppositely disposed jaws 62, 62'. The jaw 62 is cut away at 63, at a point spaced from the end of the rod, while the jaw 62', is similarly cut away at a corresponding point 63'. A drill bit 64 having the cylindrical portion 65 equipped with the radially extending lugs 66, 66' is adapted to be engaged with the drill rod. In order to connect the drill bit, the portion 65 is inserted within the bore 61 with the lugs 66, 66' in alignment with the space between the jaws 62, 62'. With the parts in this position, the bit may be forced longitudinally with respect to the drill rod until the lugs are brought opposite the cut away portion 63, 63', at which time 130

relative turning movement between the bit and drill rod will seat the lugs within the cut away portion to the rear of the overhanging enlarged portions adjacent the extremity of the drill rod.

In order to assemble the impact hammer comprising the reciprocating sleeve 38 and its associated parts, the spring 46' is first placed in position upon the sleeve, and the sleeve is in turn threaded through the washer 45', the eyelet 43, the washer 45, the spring 46, and the annulus 42. The two sections 41, 41' are then placed into cooperative relation with the groove 40, the washer 42 during this time being forced to the position shown in Fig. 4 so as to compress the springs 46, 46'. The annulus 42 is then permitted to slide over the reduced portions of the split collar under the expansion of said springs, in an obvious manner, assuming the positions shown in Fig. 1.

The parts indicated by the reference numerals 30 to 37', inclusive, which together with the impact rod 29 serves as an additional impact hammer, are assembled in a similar fashion. In other words, the several springs, washers and eyelet, are first threaded upon the rod, the springs then compressed by forcing the annulus 33 towards the abutment 30, inserting the sections 32, 32' of the split collar, and subsequently permitting the annulus 33 to engage the collar for holding the same within the groove 31 under the expansion of the springs 37, 37'.

Due to the provision of the opening at the front end of the casing and the mounting of the several parts including the cylindrical bearings 13, 14, the bushings 22, 23, and their associated parts including the worm wheel 26, the entire drill rod 29 together with the aforesaid parts may be inserted through the open end of the casing as a unit, thus facilitating the assembling of the mechanism.

Likewise due to the mounting of the driving motor 52 upon the combined closure plate and motor support, the crank shaft 56 may be readily inserted and connected with the connecting rods after which the placing of the closure plate in position will not only connect the motor to the gearing, but will bind the several parts into proper operative relation.

In operation, power is applied by means of the motor 52 to the crank shaft 56, which in turn not only rotates the drill rod 19, through means of the worm 59 and worm wheel 26, but due to the connection afforded by the pitman or connecting rods 34, 44, the impact rod 29 forming a part of one of the impact hammers is reciprocated, as well as effecting similar actuation of the impact hammer the body of which is formed by means of the slidable sleeve 38.

During each rotation of the shaft 56, the

extreme inner end of the impact rod 29 is brought into striking relation with the bottom of the bore within the drill rod, and the flanged portion 39 of sleeve 38 is likewise brought into striking relation with the inner flanged extremity 20 of the drill rod. Such mode of operation thus secures two impacts upon the drill rod during each revolution of the shaft 56, such impacts being successively caused by the alternate striking of the impact rod 29 with the bottom of the bore 21 and by similar action of the flanged portion 39 with the inner end of the rod. The striking impulses thus produced cause a reciprocation of the drill rod 19 in an obvious fashion, the said rod being free to move longitudinally with respect to its bearings and its driving wheel due to the splined connection 27.

It is obvious that the striking impacts thus produced with the parts proportioned in the manner illustrated in the drawings, is merely momentary, the compression springs employed in connection with the impact hammers permitting sliding movement of the eyelet 35 or 43, as the case may be, after the impact has been made due to the contact between the hammers and the drill rod.

As illustrated, viewing the parts as shown in Fig. 1, the crank shaft 56 is rotating in an anti-clockwise direction, and is thus bringing the flanged portion 39 into contact with the terminal flange 20 of the drill rod in order to deliver a blow, while the inner extremity of the impact rod 29 is just about to be retracted from the bottom of the bore in the said rod. It is also noted that all of the impacts from both hammers are in the same direction and are effective for moving the drill bit into the material operated upon.

During operation of the drill, the drill bit is constantly forced into intimate contact with the material being operated upon in the customary and well known manner. As the bit cuts away the material operated upon the casing 6, together with its attached parts is gradually moved towards the same by turning of the crank 8 and the feed screw rod 7.

Pressure of the bit upon the work constantly forces the drill rod 19 to move towards the left, as viewed in Fig. 1, with the result that the drill rod may be brought to the most desirable position for receiving the impact from the hammers under varying operating conditions, the compression springs of the hammers not only permitting the drill bit to assume various relative positions under variations of pressure thereon, but serving as a cushioning means to prevent undue strains upon the several parts.

It is thus seen that the invention provides a rotary-reciprocating drill which is simple, sturdy, durable and efficient in operation,

in which the several mechanisms comprising the same may be readily assembled and disassembled, either singly or collectively as units, in which repeated successive impacts are delivered to the drill rod by a plurality of impact hammers all of which are arranged in longitudinal alignment with the drill rod, in which the impact hammers are of unique construction and operatively associated with the parts to be operated upon in a novel fashion.

I claim:

1. A drill comprising a casing, a drill rod mounted thereon, a pair of movable impact hammers adapted to strike the said rod, the said hammers being permanently disposed in longitudinal alignment with the drill rod, and means having movement in a single plane for reciprocating the hammers.
2. A drill comprising a casing, a drill rod mounted thereon, an impact rod telescopically engaging the drill rod, an impact hammer slidably mounted on the impact rod adjacent the inner extremity of the drill rod, and means for reciprocating both said hammer and impact rod.
3. A drill comprising a casing, a drill rod mounted thereon, an impact rod forming a part of an impact hammer telescopically engaging the drill rod and disposed in longitudinal alignment therewith, a second impact hammer slidable on the impact rod adjacent the inner extremity of the drill rod, and means for successively bringing the said impact rod and said second named hammer into striking contact with the drill rod.
4. A drill comprising a casing, a drill rod mounted thereon provided with a hollow bore, an impact rod forming a part of a hammer slidably fitting within the bore, a bodily movable impact hammer slidably mounted upon the impact rod adjacent the inner extremity of the drill rod, and means for successively bringing the impact rod and said bodily movable hammer into striking relation with the bottom of the said bore and inner extremity of the drill rod respectively.
5. A drill comprising a casing, a drill rod mounted thereon provided with a hollow bore, an impact rod forming a part of a hammer slidably fitting within the bore, a bodily reciprocating sleeve slidably mounted on the impact rod adjacent the inner extremity of the drill rod and adapted to strikingly engage the drill rod, said sleeve having a terminal flange at one end and a

peripheral groove adjacent the other, a split collar fitting the said groove and having radially extending flanged portions providing a shoulder, an annulus encircling the said collar whereby to retain the same in cooperative relation with the groove, a pitman slidably but operatively engaging the intermediate portion of the sleeve, compression springs interposed between the said pitman and the said terminal flange and annulus, and means for actuating the said pitman and the said impact rod.

6. In combination in a drill, a reciprocating impact rod, means for reciprocating said rod including an eyelet through which the said rod passes, a fixed abutment disposed at one side of the eyelet and spaced therefrom, a spring interposed between the eyelet and said abutment, said rod being provided with an annular groove spaced from the eyelet and located at the side thereof opposite the abutment, a split annulus fitting within the said groove and positively held against longitudinal movement with respect to the said rod, the sections of the annulus having reduced portions thus providing an annular shoulder, a ring telescopically embracing the said reduced portions and adapted to abut the said shoulder, and a compression spring interposed between the said eyelet and the said ring whereby to lock the annulus in its receiving groove.

7. A drill comprising a casing, a removable end closure plate for the casing provided with an inwardly extending bearing sleeve, a similar bearing sleeve removably supported within the casing and spaced from the first named sleeve, a rotary-reciprocating drill rod mounted in said sleeves, a pair of cylindrical bushings provided with radial terminal flanges, the terminal flange on one of said bushings being removably attached thereto, the said bushings being interposed between the respective sleeves and rod and having said flanges facing each other and in abutting relation with the said sleeves, a gear encircling the rod and held against longitudinal movement by the said flanges, said gear operatively engaging the rod but mounted for free sliding movement thereupon, all of said parts being removable from the casing as a unit.

In testimony whereof, I sign my name.
ROBERT BINNIE.
